UNITED STATES PATENT OFFICE

158,733

DISPLAY SIGN

Charles L. Dwinell, Kansas City, Mo.

Application February 14, 1949, Serial No. 833

Term of patent 14 years

(Cl. D1—12)

To all whom it may concern:

Be it known that I, Charles L. Dwinell, a citizen of the United States, residing at Kansas City, in the county of Jackson and State of Missouri, have invented a new, original, and ornamental Design for a Display Sign, of which the following is a specification, reference being had to the accompanying drawing, forming a part thereof. Fig. 1 is a front elevational view of a display sign, showing my new design.

Fig. 2 is a top plan view thereof.

Fig. 3 is an end elevational view thereof; and, Fig. 4 is a rear elevational view thereof.

I claim:

The ornamental design for a display sign, as shown.

CHARLES L. DWINELL.
